UNITED STATES PATENT OFFICE.

HOWARD BARCLAY, OF VIROQUA, WISCONSIN.

DEVICE FOR FACILITATING SHINGLE LAYING.

Application filed November 27, 1920. Serial No. 426,785.

To all whom it may concern:

Be it known that I, HOWARD BARCLAY, a citizen of the United States, residing at Viroqua, in the county of Vernon and State of Wisconsin, have invented certain new and useful Improvements in a Device for Facilitating Shingle Laying, of which the following is a specification.

My invention pertains to devices for assisting or aiding in the laying of shingles, slate, tiles, and other roof coverings, whereby they may, with ease and dispatch, be applied to the roof, properly registered or aligned, and spaced apart with their centers at regular intervals to present the most attractive appearance and accomplish their function in the most efficient manner.

A particular object of this invention resides in the provision of a device of this character which has means for laying the shingles in various diagonal alignments as may be preferred and at the same time placing them with their centers uniformly apart.

A still further object of the invention resides in the construction of an alignment bar which will allow the workmen to see that the anchoring means is properly adjusted.

It is with these and numerous other objects in view, that the present invention was evolved, structures embodying the same being applicable for employment with roof covering elements or units, such as shingles, regardless of whether the same are made of natural material, as wood or slate, or whether they are a manufactured product, such as asphalt shingles.

In order that those skilled in this art may have a full understanding of the invention, I have illustrated a desirable and preferred embodiment of the same in the accompanying drawings forming a part of this specification, and throughout the various views of which like reference characters refer to the same parts.

45 In the drawings:

Figure 1 is a fragmentary face view of a roof, illustrating the use of the improved and novel structure in the application of the shingles thereto.

50 Figure 2 is a plan view of the device showing same broken away in places for convenience of illustration.

Figure 3 is a transverse section through the device.

55 Figure 4 is an edge elevational view of the device showing portions in sections,

Figure 5 is a sectional view showing in detail the construction of a portion of the device, and

Figure 6 is a view similar to Figure 1 showing another use of the device.

This embodiment of the invention comprises an alignment bar 10, preferably formed of wood equipped with a guage strip 11 secured to the bottom face thereof and extending beyond and parallel with one longitudinal edge thereof. This guage strip is preferably formed of galvanized iron. Along the edge of the guage strip 11 there are arranged at regular uniform spaced intervals 65 series of notches. Each series preferably consists of two V-shaped notches 12 and a rectangular notch 13 disposed therebetween, these notches being differently shaped only for the purpose of ready identification. Centrally 75 located intermediate these series of notches there are disposed spacing elements in the form of lips extending upwardly from the guage strip 11 as indicated at 14 and each of these spacing lips will be of an equal size. 80

A plurality of transverse, parallel, and equally spaced depressions or grooves 15 is provided on the upper face of the alignment bar 10 and are disposed so as to be in alignment with the spacing lips 14 on the guage 85 strip 11. A slot 16 is provided in each groove 15 and is arranged intermediate the ends thereof and so as to extend longitudinally of the groove. At the bottom end of each slot there is arranged a peep hole 17 90 having a width larger than the groove 15.

In each groove 15 there is seated an anchor bar 18 having its lower portion curved over upon itself thus forming a hook 19 engaging the lower edge of the alignment bar 10 and 95 the end of the hook may be readily seen through the peep hole 17. It will be understood that the grooves 15 snugly fit the anchor bar 18 so as to position them at right angles to the guage strip 11 and their accidental displacement is prevented by the bolts and thumb nuts 20 in the slot 16 which also allows the bars to be longitudinally adjusted. 100

At the end of each anchor bar 18 there is 105 provided a sharpened or pointed nose 21 extending at right angles thereto toward the roof which may be driven into the roof for holding the ends of the hooks 19 in abutment with the lower ends of the shingles in 110 the row just finished. These anchor bars 18 are preferably but slightly longer than

the shingles as shown in Figure 1. Each bar 18 is provided with a plurality of apertures 22 so that nails may be passed therethrough and driven into the roof for holding the anchor bar when near the top of the roof. A set practical for roof laying would consist of a plurality of devices such as above described and they would be placed end to end.

The operation of the appliance is substantially as follows:

Assuming that several rows of shingles have been laid and fastened to the roof, as shown in Figure 1, and that the workman is about to lay the next row of shingles, he places the alignment bar 10 over the lower portions of the shingles A and pushes the bar upwardly until he sees that the ends of the hooks 19 abut the lower edges of the shingles A by looking through the peep holes 17. The next step is to see that the U-shaped notches 13 coincide with the spaces between the shingles A. The noses 21 will now be driven into the roof. He now will place the shingles so that one of their shorter edges abuts the alignment bar 10 between the spacing lips 14. In this way the row of shingles is positioned, and they are nailed in place after the whole row has been laid out, or the workman may nail them down in succession as he proceeds with the positioning. After the row has been secured to the roof, the workman loosens the noses 21 and moves the alignment bar 10 and its associated parts downwardly to free the guage rod 11 from under the shingles A. He now moves the bar 10 and its associated parts to an analogous position on shingles B as they were on the shingles A. It is of course to be understood that all rows of shingles are laid in this way, the workman starting at the lower edge of the roof and working upwardly, as is the ordinary method of shingle application.

In using the guage rod 11 as just described, that is, so that the rectangular notches 13 register with the spaces between the shingles it will be noted that the spaces between the shingles will be located centrally of the shingles therebeneath and so as to be in diagonal alignment as indicated by the dotted line C. Some building contractors and architects prefer, however, to have the spaces between the shingles adjacent one edge of the under

shingles. When it is desired to use this latter plan the V-shaped notches 12 will be placed in alignment with the spaces between the shingles. When the more defined and conspicuous rows run upwardly and to the right, the V-shaped notch to the left of the spacing lips 14 should be placed over the spaces between the shingles A of the preceding row as illustrated in Figure 6; if to the left, the V-shaped notches to the right of the spacing lips must be used.

Obviously, the invention is not limited and restricted to the precise and exact details of construction as illustrated and described, because it is susceptible of a variety of embodiments, and many minor mechanical changes may be made in such preferred incorporation of the invention without departing from the substance and essence of the invention and without the sacrifice of any of its substantial benefits and advantages.

Having thus described my invention what I claim as new is:

1. In a structure of the character described, the combination of an alignment bar and a guage strip attached thereto and provided with notches for the purpose specified, spacing elements arranged at intervals along the guage strip, the alignment bar being provided with transverse grooves, and anchoring bars detachably seated in said grooves.

2. In a structure of the character described, the combination of an alignment bar and a guage strip attached thereto and provided with notches for the purpose specified, spacing means positioned at intervals along the guage strip, said alignment bar being provided with a plurality of transverse grooves disposed so as to be in alignment with the spacing means and at right angles to the longitudinal edges of the alignment bar, the alignment bar provided with a plurality of peep holes, and anchoring bars disposed in said grooves and having their lower ends hooked so that the end of the hooks may be seen through the peep holes.

In testimony whereof I affix my signature in presence of two witnesses.

HOWARD BARCLAY.
